UNITED STATES PATENT OFFICE.

EDWARD AMBROSE, OF TROY, NEW YORK, ASSIGNOR TO SAMUEL B. SEXTON, JR., OF BALTIMORE, MARYLAND.

DESIGN FOR A KITCHEN-RANGE.

SPECIFICATION forming part of Design No. 25,812, dated July 21, 1896.

Application filed May 1, 1896. Serial No. 589,908. Term of patent 14 years.

To all whom it may concern:

Be it known that I, EDWARD AMBROSE, a citizen of the United States, residing at Troy, in the county of Rensselaer and State of New York, have invented and produced a new and original Design for a Kitchen-Range, of which the following is a specification.

The figure shown in the drawing is a perspective view showing my design for a kitchen-range.

The features of my design are the oven-door A, with its surface ornamentation as shown, and the door for the fire-grate B, with vertical slots in its lower part and surface ornamentation; also, the two lower ash-box doors C, each having the surface ornamentation shown, and the side plate D, the surface of which is also provided with ornamental work.

All the parts thus far described are comprised in the range proper, which in general has a rectangular outline.

The two doors C' of the elevated warming-oven are like the ash-box doors, but the upper curved plate F above the warming-oven

and at the front of the horizontal cylindrical boiler has a vine-ornamented surface.

Having thus described my design, what I claim is—

1. The design for a kitchen-range, as herein shown and described.
2. The design for an oven-door, as herein shown and described.
3. The design for the fire-grate door, as shown and described.
4. The design for the two doors for ash-box or warming-oven, as herein shown and described.
5. The design for the side plate of a kitchen-range, as herein shown and described.
6. The design for the curved plate, F, covering the boiler as herein shown and described.

In testimony whereof I affix my signature in the presence of two witnesses.

EDWARD AMBROSE.
